UNITED STATES PATENT OFFICE.

SVAN NORDEN, OF CRANSTON, RHODE ISLAND.

MACHINE FOR TIPPING SHOE-LACES.

1,348,660.

Specification of Letters Patent.

Patented Aug. 3, 1920.

Application filed March 20, 1919. Serial No. 283,758.

To all whom it may concern:

Be it known that I, SVAN NORDEN, a citizen of the United States, residing at Cranston, in the county of Providence, State of Rhode Island, have invented certain new and useful Improvements in Machines for Tipping Shoe-Laces, of which the following is a specification.

My invention relates to improvements in machines for affixing tips to shoe-laces, corset-laces or the like. The object of my improvement is to provide an automatic machine for rolling a metal blank around the end of the lace and forcing its overlapping edges together to grip the fabric to secure the tip firmly thereto. To accomplish this object I provide means for holding one edge of the tip-blank in place while rolling its other edge over the lace, and for also locating and holding the end of the lace in proper position during the tipping operation. My improvements are embodied in a machine which may be adapted for applying either straight or tapered tips to the lace, and which operates in such a manner as to give a neater and smoother appearance to the finished article, while also tending to increase its durability by attaching the tip more securely in place.

The manner and means for carrying out these improvements are fully described in the following specification, illustrated by the accompanying drawings, in which like reference characters designate like parts. In the drawings:

Fig. 1 is a side elevation of my improved machine showing its parts in retracted position before starting to operate on the tip-blank;

Fig. 2 is an enlarged perspective view of one form of blank which is rolled around the lace to form the finished tip;

Fig. 3 is a similar view of a portion of the lace showing this type of blank applied to its end to form a tapered or conical tip;

Figs. 4, 5 and 6 are enlarged detail views of the dies which operate on the blank to roll it around the tip, showing different stages in the tipping process;

Fig. 7 is a plan view of the dies, shown in slightly reduced scale;

Figs. 8 and 9 are detail views of a set of dies of slightly modified form for use in attaching straight tips; and

Fig. 10 is an enlarged perspective view showing the straight tip applied to the lace.

Referring first to Fig. 1, the main frame 2 of the machine comprises a standard or upright 3 formed with a flat base 4 having lugs or ears 5 on its sides through which are inserted screws 6 for fastening it to a suitable bench or table 7. At its forward end the upright 3 is reduced in width at 8 and cut away at 9 to form an inclined rest or ledge on which the fixed die C is seated against a squared shoulder 10, being held in place by a bolt 11. Projecting rearwardly from the standard 3 and overhanging the base 4 is an inclined shelf 12 which is of greater width than the main portion of the frame. The shelf 12 is slotted longitudinally throughout its length to provide a rectangular track or guideway 13 adapted to receive a slidable, flat bar or plate 14. The bar 14 is held in place in the guideway 13 by a cover or plate 15 fastened to the upstanding sides of the shelf 12 by means of screws 16. Mounted on the forward end of the bar 14 is the movable die D which co-operates with the fixed die C for affixing the tip to the lace.

Projecting up through an opening 19 in the base 4 is a curved lever 20 which is pivoted on a pin 21 driven through the sides of the opening. The upper arm of the lever 20 reaches through an elongated aperture 22 in the bottom of the shelf 12 and is formed with a circular end 23 which engages the sides of a slot 24 cut through the bar 14. The lower arm of the lever 20 extends forwardly beneath the table 7 on which the frame 2 is fastened and is held in raised position by a coiled spring 25 anchored to a hook 26 on the base 4. Connected to the outer end of the lever 20 is a rod or link 27 reaching down to a treadle or foot lever, not herein shown, from which the machine is operated. The lever 20 might be formed with a handle at its outer end, but I have found it preferable to operate it from a treadle in order to leave the hands free for placing the tip-blanks in the machine and for applying the lacing ends thereto for tipping. When the forward end of the lever 20 is depressed it will cause the bar 14 to be slid forwardly in its guideway 13 to carry the movable die D toward the fixed die C in the manner as hereinafter more fully explained. The spring 25 acts to return the lever 20 to first position, after the tipping operation has been completed, and a stop-screw 27 is screwed through the end of the shelf 12 to contact

with the upper arm of the lever to limit its rearward movement as the die D is withdrawn.

Referring to Figs. 1 and 7, the fixed die C is constructed in the form of a rectangular block having its under side cut away at 29 to form a plate-like extension 30 which overhangs the ledge 9 on the frame 2 in parallel, spaced relation therewith. The forward end of the slideable bar 14 is cut away at its end to form a bearing or seat 31 for a flat plate 32 which also rests on the end of the ledge 9 and is adapted to slide in under the extension 30, of the die C, as shown in Fig. 1. The plate 32 is formed with a rectangular block or key-piece 33, see Fig. 7, projecting above its upper face and adapted to serve as a guide for the die D which is arranged to have a slight sliding movement relatively to the plate. As shown more particularly in Fig. 7, the die D takes the form of a flat plate which is cut away at its center to provide two opposite, parallel legs 34, 34 straddling the sides of the block or key 33 on the lower plate 32. Overlying the top of the die D is a third flat plate 35, see Fig. 1, which is fastened by pins or rivets 36 to the top of the key 33 to prevent the die from rising up out of place thereon. A bolt 37 extends down through the plate 35, die D and plate 32, and is screwed into the bar 14 to secure the several parts in place thereon with the end of the plate 32 abutting a shoulder 38 to prevent it from turning. As before explained, the die D is adapted to slide back and forth on the plate 32 while being guided by the key 33, and this sliding movement is limited by a stop-pin 39, see Fig. 7, which is driven down through the top-plate 35 and projects into an enlarged hole 40 in the die. Inserted between the forward edge of the key 33 and the end of the opening between the legs 34, 34 of the die D is a bow-shaped spring 41 which tends to maintain the die in its forward position with the side of its hole 40 bearing against the stop-pin 39.

Referring particularly to the enlarged views, Figs. 4, 5 and 6, the forward end of the die D is beveled off on the top at 42 and undercut along its lower edge to provide an overhanging curved lip 43. The concaved under face of the lip 43 is formed concentric with an upstanding curved shoulder or ledge 44 on the plate 32, these two faces registering to form a half circle when the die D is in its retracted position as illustrated in Fig. 6. When, however, the die D is slid forward on the plate 32, under the action of the spring 41, see Figs. 4 and 7, the lip 43 is advanced beyond the ledge 44 so that its under edge projects beyond and overhangs the top of the ledge to form an abrupt shoulder 45. The purpose of this arrangement is to provide an overhanging abutment for holding

one edge of the tip-blank B in place while its opposite edge is rolled up over the end of the lace L as shown in Fig. 5 and more fully explained hereinafter.

Referring now to Fig. 2, the tip-blank B consists in a relatively thin, flat strip of sheet-metal, and as here illustrated its opposite marginal edges are inclined toward each other at one end. This provides that when the blank B is rolled around the end of the lace L it will assume a slightly conical shape, to form a more or less pointed tip T as shown in Fig. 3. In some cases, however, where a straight tip is required the blank is made rectangular in shape with its marginal edges parallel. In either case my improved form of blank is preferably constructed with its opposite edges rolled or bent over to form upstanding curved lips b, b. The upwardly-bent edges b of the blank serve to facilitate the operation of rolling it around the lace as the dies start to operate against its sides. For this purpose it is only necessary to have one of the edges bent or curled upwardly, but for the sake of symmetry, and to provide for more convenient manufacture of the blanks in stamping them out of the metal sheet, I have found it preferable to bend up both edges. As shown in Fig. 2, the blank B is usually punched with a series of perforations which upsets the strip on its upper face to form sharp-edged projections b', b'. These projections or prongs b' are adapted to bite into the fabric when the blank B is clenched around the lace whereby to grip its end and prevent the tip from pulling off.

Referring to Figs. 4, 5 and 6, the overhanging extension 30 of the fixed die C has its forward end beveled off at top and bottom, the under beveled face 49 terminating in a semi-circular recess 50. This concaved recess 50 forms the working-face of the die C, its lower edge taking the form of a sharp, pointed prow 51 where it meets the top of the plate 32 which slides beneath it. As the movable die D is slid forward toward the fixed die C the end of the plate 32 strikes against the shoulder 29 at the end of the recess below the extension 30 on the die C to act as a stop to prevent further movement of the die D, see Fig. 6. When the die D is carried into this position by the sliding movement of its support or bar 14, its upper, beveled face 42 comes into contact with the opposite, under beveled face 49 on the die C and this engagement serves to slide the die D back on the plate 32 against the action of its spring 41, see also Fig. 7. As the two dies thus come into register to act on the blank B, in the manner as hereinafter more fully explained, the concaved lip 43 on the die D is brought into concentric relation with the upstanding curved shoulder 44 on the plate 32 and with the concaved

recess 50 on the die C, forming a complete circle with the working-faces of the dies inclosing the finished tip as shown in Fig. 6.

It will be noted from reference to Fig. 7 that the opposite, undercut working-faces 43 and 50 of the dies D and C and the up-standing ledge 44 of the plate 32 are inclined slightly toward each other in a horizontal plane to conform to the taper of the edges of the blank B. When, however, a straight-sided blank is to be used for tips of the type shown in Fig. 10, then the working-faces of the dies and the shoulder 44 on the plate 32 are made parallel as illustrated in Figs. 8 and 9.

Set into a recess on one side of the plate 32 is a vertical plate 53, see Figs. 1 and 7, fastened in place by a screw 54, and serving as a stop or limit for engaging the end 20 of the blank B to locate it in position in relation to the dies. Fastened to the top of the plate 53, by means of a screw 55 and dowel pin 56, is a flat spring 57 having an arm 58 bent downwardly against the inclined face 42 of the die D. At its forward end the arm 58 has fork-like tines or fingers 59 which are curled upwardly at their outer extremities. The fingers 59 are adapted to bear against the side of the lacing L, 25 when the movable die D moves forward toward the fixed die C, to carry it over into position and hold it in place to be received within the edge of the blank B as the latter is bent therearound, see Fig. 4. As the die D slides up into register with the die C the fingers 59 enter grooves 60 therein, the bottom of the grooves being inclined upwardly whereby the end of the spring-arm 58 is lifted slightly to raise its fingers 59 30 out of the way as the working-faces of the dies act on the finished tip, see Figs. 5 and 6. Having now described the construction and arrangement of the several parts of my improved apparatus, its method of operation will next be explained:

With the parts of the machine in the position shown in Fig. 1 the blank B is laid flat on the top of the plate 32 with its end against the side of the stop-plate 53 to locate it in position in relation to the dies. With the die D retracted the spring-arm 58 is withdrawn sufficiently to permit the blank B to be conveniently set in place, and the slope of the plate 32, on which it is laid, 55 causes it to slide down into position with its edge b resting against the working face of the die C, see Fig. 4. The end of the lacing L to be tipped is next laid in place on the top of the blank and the operator then depresses 60 the treadle or foot-lever to rock the lower arm of the lever 20 downwardly. This action causes the upper arm of the lever 20 to slide the bar 14 forward and downward in its guideway 13 to cause its projecting plate 65 32 to be slid in under the overhanging ex-

tension 30 of the die C. As before explained, the plate 32 carries the die D and as the latter moves forward its bottom edge 45, which overhangs the shoulder or ledge 44 on the plate, will ride into position above 70 the curled-up edge b of the blank B as shown in Fig. 4. Meanwhile, the forward movement of the die D will also have carried the curved end of the spring-arm 58 against the side of the lacing L and the latter will 75 have been pushed or slid over against the under-beveled face of the die C. Now, as the die D continues to advance it will push the blank B against the die C to roll its forward edge up around the lace L in the manner as illustrated in Fig. 5. This rolling action is caused by the edge b following the concaved face 50 on the die C as the side of the blank is pried or wedged away from the plate 32 by the sharp-edged prow 51. 80 While the forward edge b of the blank B is thus being rolled around the lace L, the latter being maintained thereagainst by the spring-arm 58, the opposite rearward edge b is held down against the plate 32 by the 85 overhanging edge or abutment 45 on the die D. As the edge b of the blank being operated upon rolls or curls over the top of the lacing L the tines or fingers 59 at the end of the spring-arm 58 slide into the 90 grooves 60 in the die C, see Figs. 5 and 7, and are thereby lifted out of the way when the dies are finally brought together. As the die D comes into register with the die C the beveled face 49 on the latter engages the 95 opposite inclined face 42 on the die D to hold the latter from further movement while the plate 32 moves forward, this action being provided for by the yielding of the spring 41, see Fig. 7, as before explained. As the die D is held in this manner the ledge 44 on the plate 32 slides out from under the overhanging edge 45 of the die to release the edge b of the blank B which has been held 100 thereunder. It will be understood that the 105 sliding movement of the die D on the plate 32 is limited by the engagement of the pin 39 with the sides of the hole 40, see Fig. 7. This provides that when the concaved edge 43 of the die D comes into concentric register with the curved edge of the ledge 44 on the plate 32 the die will be held fast with the plate. Therefore, as the plate 32 reaches the end of its stroke, with its end engaging the shoulder 29 on the die C, the two working-faces of the dies D and C will be pressed 115 firmly against the sides of the blank B to clench its overlapping edges together as shown in Fig. 6. This final clenching action of the dies causes the prongs b' on the inner 120 surface of the blank B to bite into the sides of the lacing, while also tending to set the blank to prevent its edges from springing apart. In this way the blank B is caused 125 to be constricted snugly around the lacing 130

while compressing the latter slightly, as shown in Fig. 6, so that when the tip is removed from the dies it will have a smooth, practically unbroken joint where its end 5 overlaps the lace and will present an extremely neat and finished joinder therewith while being held firmly and securely in place thereon. After the tipping operation is completed the treadle is released and the 10 lever 20 will be returned to first position, as shown in Fig. 1, under the action of the spring 25. The rocking back of the lever 20 withdraws the bar 14 and opens the dies to release the finished tip and the parts are 15 thus returned to position for receiving and operating on a fresh blank.

The conical or pointed form of tip T shown in Fig. 3 is usually applied to round laces, so-called, but with flat, tubular laces 20 a straight tip is employed. The straight type of tip T' is illustrated in Fig. 10 and is affixed to the lace in substantially the same manner as above explained in connection with the conical tip. For a straight tip the 25 blank is made rectangular with its marginal edges parallel, and the dies C and D have parallel working-faces as shown in Figs. 8 and 9. During the process of rolling this form of tip around the lace the 30 end of the latter is doubled on itself or folded together, as indicated in Figs. 8 and 9, while the side of the blank curls around it. As shown particularly in Fig. 9, the edge b 35 of the blank curls into the folded seam 1 of the fabric and takes a firm grip thereagainst, while the opposite edge of the blank is clenched against it. In this way the edge 40 of the blank is caused to take a firm bite on the lace L to secure the tip against pulling off and the finished tip T' will have a closer fitting and neater appearance as shown in Fig. 10.

It will be observed from the foregoing that my improvement provides a practically 45 automatic, quick-acting apparatus for applying tips to shoe-laces while clenching them firmly in place thereon. The tips are affixed in place by a method which insures a firm 50 grip on the end of the lace, to prevent them from pulling off under hard usage, and the finished tip has a particularly smooth and neat appearance which enhances the commercial value of the completed lacing.

Various modifications might be made in 55 the structure and arrangement of the parts of my improved apparatus without departing from the spirit or scope of the invention, therefore, without limiting myself to the exact embodiment herein shown and described, what I claim is:—

1. In a machine for tipping corset- or shoe-laces, the combination of a set of dies arranged to act against the opposite edges 60 of the tip-blank to roll the latter around the lace, a substantially flat rest on which

the blank lies, means to operate said dies, means engaging the marginal edge of the blank to hold it flat against the rest while its other edge is curled around the lace, and means to release the edge-holding means as 70 the dies come into register.

2. In a machine for tipping corset- or shoe-laces, the combination with a pair of coöperating dies having a substantially flat rest on which the tip-blank lies and concaved working-faces adapted to act against the opposite edges of the blank to curl the latter around the lace, of means to carry the dies together, and a releasable abutment 75 on one of the dies for engaging one edge of the blank to hold it flat against the rest until the other edge has been bent around the lace contiguous to said first mentioned edge.

3. In a shoe-lace tipping machine, the 80 combination with a pair of coöperating dies having concaved working-faces for acting against the edges of a flat tip-blank and a substantially flat rest against which the blank lies, of means for carrying the dies 85 into coöperative relation, means on one of the dies overhanging one edge of the blank to hold the latter flat against the rest while its other edge is rolled around the lace, and means for withdrawing the holding-means 90 as the dies come into register to clench the tip around the lace.

4. In a tipping-machine for shoe-laces or the like, the combination with a pair of coöperating dies having concaved working- 100 faces for acting against the opposite edges of a relatively flat tip-blank and a substantially flat rest against which the blank lies, one of said dies having an overhanging abutment adapted to overlie one edge of the 105 blank, to hold the latter flat against the rest, means to carry the dies together to cause the opposite edge of the blank to be bent around the tip, and means to withdraw the edge-holding abutment from engagement with 110 the blank when the dies are brought into register.

5. In a tipping-machine for shoe-laces or the like, the combination with a relatively 115 flat rest for the tip-blank having a raised ledge for engaging one edge of the blank, a die having an undercut concaved working-face, said die slideable on the blank-rest to overhang its ledge to hold the blank flat against the rest, a second die having a concaved working-face for acting against the opposite edge of the blank to curl it around the lace, means to actuate the dies to cause them to operate on the blank, and means acting to withdraw the first die from above the 120 edge of the blank as the working-faces of the dies come into register to clench the blank around the lace.

6. In a tipping-machine for shoe-laces or the like, the combination with a pair of 130

dies having coöperating working-faces adapted to act against the opposite edges of the tip-blank to roll the latter around the lace, of resiliently-operated means arranged to overlie one edge of the blank to hold it in place as its other edge is curled around the lace, and means to displace the holding-means to release the edge of the blank as the dies come into register to clench the tip in place on the lace.

7. In a tipping-machine, the combination with a rest for the tip-blank having an up-standing abutment for engaging one edge of the blank, a die slidable on the rest and provided with a working-face normally positioned above the blank, resilient means for maintaining said die with the edge of its working-face advanced beyond the abutment on the rest to overhang the edge of the blank to hold it from bending, a second die having a working-face adapted to coöperate with that on the first die, and means to operate the dies to bring their working-faces into register while forcing the sliding-die back to align its working-face with the abutment on the rest.

8. In a tipping-machine, the combination with a die having a concaved working-face adapted to act against one edge of the tip-blank to roll it around the lace, of a rest for the blank arranged to slide beneath the working-face of the die and provided with a raised abutment for engaging the rearward edge of the blank, a second die mounted to slide on the rest and provided with a working-face arranged thereabove, means for normally maintaining the second die with the edge of its working-face advanced beyond the abutment on the rest to overlie the edge of the blank to hold it thereagainst, and means for sliding the rest to carry the dies into engagement to act on the blank while displacing the slidable die to bring the working-faces into register to clench the tip around the lace.

9. In a tipping-machine, the combination with a fixed die having an undercut concaved working-face on its forward end, of a slidable bar, a plate-like rest carried by the bar to adapt it to slide beneath the working-face of the fixed die, said rest provided on its top with a raised abutment for engaging the edge of the tip-blank carried thereon, a movable die carried by the rest and slidable thereon to a limited extent, said die having a

concaved working-face arranged above the rest, a spring for maintaining the movable die in advanced position on the rest with the edge of its working-face overhanging the abutment thereof, and means to operate the slide whereby the movable die is carried against the fixed die to force it back on the rest to bring its working-face into alinement with the abutment thereof while registering it with the working-face of the fixed die.

10. In a tipping-machine for shoe-laces or the like, the combination with a pair of dies having a flat rest on which the tip-blank lies and working-faces adapted to coöperate to act on the opposite edges of the blank to roll it around the lace, of means engaging one edge of the blank to hold the latter flat against the rest, and means for holding the end of the lace in place to be received within the rolled-over edge of the blank.

11. In a tipping-machine for shoe-laces or the like, the combination with a pair of dies having coöperating working-faces for acting against the edges of the tip-blank to roll it around the lace, of means for holding the end of the lace in place as one edge of the blank is bent around it, and means to carry the lace-holding means out of the way as the dies are brought together to clench the tip in place on the lace.

12. In a tipping-machine for shoe-laces or the like, the combination with two dies movable one in relation to the other to cause their working-faces to act against the edges of the tip-blank arranged between them to roll it around the lace, of a yieldable spring carried by one of the dies to adapt it to engage the end of the lace to move it into position to be received within the edge of the blank as the latter is rolled around it.

13. In a tipping-machine for shoe-laces or the like, the combination with two coöperating dies for acting on the tip-blank to roll it around the lace, of means to carry the dies together, and a spring arm projecting from one die into position to engage the end of the lace to hold it in place as the blank is rolled around it, the end of said arm being adapted to engage an inclined face on the opposite die to cause it to be raised out of the way as the dies come together.

In testimony whereof I affix my signature.

SVAN NORDEN.
